US00D954732S

(12) **United States Design Patent** (10) **Patent No.:** **US D954,732 S**
Butcher et al. (45) **Date of Patent:** **** Jun. 14, 2022**

(54) **DISPLAY SCREEN OR PORTION THEREOF
WITH GRAPHICAL USER INTERFACE**

(71) Applicant: **Apple Inc.**, Cupertino, CA (US)

(72) Inventors: **Gary Butcher**, Los Gatos, CA (US);
Lynne Devine, San Francisco, CA (US); **Jennifer Patton**, Cupertino, CA (US); **Aled Williams**, Llandeilo (GB)

(73) Assignee: **Apple Inc.**, Cupertino, CA (US)

(**) Term: **15 Years**

(21) Appl. No.: **29/738,901**

(22) Filed: **Jun. 20, 2020**

(51) **LOC (13) Cl.** **14-04**

(52) **U.S. Cl.** **USPC D14/486**

CLAIM

The ornamental design for a display screen or portion thereof with graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front view of a display screen or portion thereof with graphical user interface showing the claimed design; and,

FIG. 2 is a front view of another embodiment thereof. The broken lines in the figures show a display screen or portion thereof, and form no part of the claimed design.
